DESIGN FOR A HANDLE HINGE BRACKET OR SIMILAR ARTICLE

Allen F. Beck, Columbus, Ohio, assignor to The Clark Grave Vault Company, Columbus, Ohio,
a corporation of Ohio

Application September 5, 1933, Serial No. 49,204

Term of patent 14 years

To all whom it may concern:

Be it known that I, ALLEN F. BECK, a citizen of the United States, residing at Columbus, in the county of Franklin and State of Ohio, have invented a new, original, and ornamental Design for a Handle Hinge Bracket or Similar Article, of which the following is a specification, reference being had to the accompanying drawing, forming a part thereof.

Fig. 1 is a perspective view of a handle hinge bracket, showing my new design;

Fig. 2 is a transverse vertical sectional view taken on the line II—II of Fig. 1.

I claim:

The ornamental design for a handle hinge bracket or similar article, as shown.

ALLEN F. BECK.
